DULL BIT INDICATOR

Walter J. Bielstein, Houston, Tex., assignor, by
mesne assignments, to Standard Oil Develop-
ment Company, Elizabeth, N. J., a corporation
of Delaware

Application June 15, 1949, Serial No. 99,249

7 Claims. (Cl. 255—61)

1

This invention relates to a drill bit used for drilling boreholes into subsurface formations. More particularly, this invention relates to a drill bit which, when it is worn by a pre-determined amount during drilling operations, will give a signal of such wear at the surface of the earth.

In the drilling of boreholes into subsurface formations by the rotary drilling method, particularly in drilling boreholes for the production of minerals, such as oil and gas, the drill bit attached to the end of the drill stem is subjected to conditions which cause rapid wear of the cutting edges of the bit blades. The blades of several bits are ordinarily worn off in drilling such a well. Of course, when the blades are worn off a particular bit, the drilling crew must pull the drill stem out of the hole and replace the worn bit with a new bit before resuming drilling operations. When conventional bits are employed in such operations, no positive method is available for determining the point when the cutting blades of the drill bit are worn to such an extent as to require replacement of the bit; consequently, the selection of the time when the drill bit should be removed from the hole is wholly within the judgment of the drilling crew. As would be expected, conventional drill bits are sometimes removed from the hole before the blades have been worn to the point where the drill bit should really be replaced. On the other hand, and perhaps more commonly, the drill stem is sometimes not withdrawn from the hole and the bit replaced until long after the blades have been worn to such an extent that little or no hole is being made. As a matter of fact, drilling is sometimes continued until the bit blades have been completely worn off the bit body and the bit body itself damaged by wear.

Although excessive wear of the cutting edge of the bit blades is the most frequent reason for replacement of conventional drill bits, it sometimes happens that the bit should be replaced because it has become worn "out of gauge." Here again the drilling crew has no positive means of knowing when the bit has become so worn. A drill bit is said to be worn "out of gauge" when the reaming edges of the bit blades have been worn to such an extent that the diameter of the hole being made is smaller than may conveniently be tolerated. For example, the diameter of a hole drilled with a bit having worn reaming edges may not be sufficiently great to permit the free passage of a new unworn drill bit subsequently introduced into the hole. When this condition exists, the borehole walls must be enlarged

2

by reaming in a suitable manner as with a new bit. Not only does reaming consume time but it also entails the risk of a stuck drill bit.

It is an object of this invention to provide a drill bit which, when worn by a pre-determined amount, will cause an increase in fluid pressure in the mud stream used with the drill string and thus give a signal to the drilling screw indicating that the drill bit should be removed because of excessive wear.

It is a further object to provide a drill bit, the body of which will not be damaged during drilling operations and in which the construction is such that repair of the used bit is convenient and simple.

The foregoing objects, as well as other advantages, are attained by the present invention as will be apparent from the following detailed description taken in connection with the accompanying drawings in which

Fig. 1 is a front view, partly in cross section, of a drill bit constructed in accordance with the present invention with the parts thereof in their relative positions during normal drilling and before the bit blades have become excessively worn;

Fig. 2 is a view taken along the line II—II of Fig. 1;

Fig. 3 is a front view, partly in cross section, of the embodiment of Fig. 1 with the parts thereof in their relative positions when the bit blades have become excessively worn; and

Fig. 4 and Fig. 5 are front views of a modification of the embodiment of Fig. 1.

Referring to the drawing in which like numerals refer to like elements throughout, the embodiment shown in Figs. 1 to 3, inclusive, comprises a bit consisting of a body 10 and blades 11 and 12. The body 10 may be affixed to the lower end of a drill stem 13 by any suitable means, such as threads, the said drill stem being of conventional design fluidly connectible with the source of drilling fluid under pressure. Body 10 is provided with a hollow internal portion 14 in fluid communication with drill stem 11 when drill stem 13 is connected with body 10. Ducts 15 and 16, conventionally termed "eyes" or "water courses," fluidly connect the hollow portion 14 of body 10 with the outer surface of said body, the outer terminus of ducts 15 and 16 being above the upper edge of bit blades 11 and 12, respectively, and normally directed in front of the cutting edges 17 and 18, respectively, of said blades. Bit blades 11 and 12 may be of any desired design and preferably are made of hard, tough, metallic materials. The reaming edges

19 and 20 of bit blades 11 and 12, respectively, are approximately parallel to each other and to the longitudinal axis of body 10. Cutting edges 21 and 22 of bit blades 11 and 12, respectively, may be perpendicular to the axis of body 10 though they may taper outwardly and downwardly as shown in the drawing. The cutting edge 18 of bit blade 11 is disposed approximately 180° from the cutting edge 17 of bit blade 12. Bit blades 11 and 12 may be incorporated into the lower end of body 10 in any suitable manner and are normally affixed to the said body by welding. The drawing shows a dual-bladed bit for the sake of simplicity although it will be understood that the bit of my invention may have a greater number of blades.

The structure heretofore described is conventional to ordinary drag bits. In accordance with the present invention, the aforesaid structure is modified by providing means within the bit body for closing at least one but not all of the water courses to the passage of drilling fluid when the bit blades have become worn by a pre-determined amount during drilling operations. The drawing shows two water courses, namely 15 and 16, with means mounted in the bit body for closing water course 16 to the passage of drilling fluid when blades 11 and 12 have been worn by a pre-determined amount. The aforesaid means consists of a cylindrical duct 23 extending through bit body 10 and fluidly connecting internal hollow portion 14 with the outer surface of bit body 10. Duct 23 is positioned in body 10 so that its outer terminus is located in body 10 adjacent the face 24 of bit blade 12, which is opposite the cutting face 17 thereof. Duct 23 consists of an enlarged cylindrical portion 25 and a smaller cylindrical portion 26, the juncture of these two portions forming inwardly extending shoulder 27. Mounted within cylindrical portion 25 of duct 23 is piston 28 which is arranged to fit slidably therein. Mounted on piston 28 is sealing ring 29 which provides a fluid-tight seal between piston 28 and the walls of enlarged portion 25 of duct 23. Piston 28 is mechanically connected to a retaining ring 30 by means of piston rod 31. Retaining ring 30 and consequently piston 28 is biased upwardly by means of spiral spring 32 which abuts against the ring 30 and shoulder 27. Piston stops 33 project into duct 23 and limit the downward movement of piston 28. Piston 28 defines a recess 34 in its side wall while duct 23 also carries a matching recess 35, recesses 34 and 35 being adapted to receive a shear pin 36 made of suitable metallic material. Duct 23 also defines near its upper end grooved recess 37, while piston 28 carries expansible ring 38 which is adapted to expand into recess 37 when piston 28 is so positioned in duct 23 that expansible ring 38 is opposite recess 37.

The outer end of portion 26 of duct 23 is normally sealed against the passage of fluid therethrough by any suitable means and may be closed by means of a plug 39, preferably of metal, to which is affixed on its inner end sealing diaphragm 40. Sealing diaphragm 40 may be made of any suitable material which will provide a fluid-tight seal preventing the escape of fluid from duct 23 past plug 39. Synthetic rubber or natural rubber may suitably be employed for this purpose. Plug 39 with sealing diaphragm 40 affixed thereto is normally held within portion 26 of duct 23 by means of rod 41 which is affixed to plug 39 and to blade 12 by suitable means, such

as by welding. Rod 41 is of sufficient length to extend onto blade 12 to a point at least below the lower edge 43 of body 10. The highest point along blade 12 at which rod 41 is welded thereto will be the point at which bit wear is indicated, as will be hereinafter more fully described. Rod 41 may also be positioned in close proximity to the reaming edge 20 of bit blade 12, if desired, so as to indicate the point at which the bit has become worn "out of gauge," as will also be more fully described hereinafter.

Sealing flapper 42, which is so constructed as to present a face 48 adapted to seal the inner end of duct 16 and which may be suitably made of hardened rubbery material or a satisfactory substitute therefor, is connected by rod member 43 to a pivot 44 located on the inner surface of bit body 10 for arcuate movement about pivot 44. Rod member 43 carries a link 45 by means of which rod member 43 is mechanically connected to link 46 carried by the head of piston 28 through linked connecting member 47. Flapper 42, rod 43 and pivot 44 are so positioned with respect to duct 16 that when flapper 42 is moved arcuately and downwardly by downward and outward movement of piston 28, the face 48 of flapper 42 will cover the inner terminus of duct 16 and prevent the passage of drilling fluid from the interior hollow portion 14 of body 10 to the exterior of the said body.

In order to prevent any substantial downward movement of piston 28 in duct 23, while plug 39 is in place in portion 26 of duct 23, the space between piston 28 and plug 39 is filled with a suitable liquid which may be lubricating oil or any other substantially non-compressible fluid which will remain in a liquid state while the device of my invention is in use.

The structure of my invention having hereinbefore been fully described, its mode of operation will now be briefly indicated. Fig. 1 of the drawing shows the device of my invention in the position it assumes during normal drilling operations before the bit blades 11 and 12 have been worn to the point at which replacement is required. Fig. 3 shows the position of the device of my invention after the bit blade has been worn to a point to which the bit should be replaced.

Referring first to Fig. 1, it will be noted that flapper 42 is in a position out of contact with the inner terminus of duct 16 while piston 28 is positioned near the upper inner end of portion 25 of duct 23 and are so held by reason of the upward bias exerted by spring 32. Piston 28 may be further held against both upward and downward movement by means of shear pin 36. Thus, flapper 42 is maintained in a substantially upright position out of contact with the inner terminus of duct 16 until bit blades 11 and 12 are worn to a point as indicated in Fig. 3, at which time that portion of rod 41 welded to blade 12 will also be worn off, thus permitting plug 39 and sealing material 41 attached thereto to be forced out of portion 26 of duct 23 by reason of the downward pressure exerted by the drilling fluid against the head of piston 28. Of course, shear pin 36 is made of a material which will shear when plug 39 and material 41 are removed from their normal position closing duct 23. Piston 28 then moves downwardly in portion 25 of duct 24 until its lower edge abuts against stops 33, at which time flapper 42 is carried against the inner terminus of water course 16, thereby closing same to the passage of drilling fluid as shown in Fig. 3. With water course 16 so closed, the

total nozzle area of the bit is markedly decreased and consequently the pressure of the drilling fluid in portion 14 of bit body 10 and in drill stem 13 is markedly increased, thereby indicating to the drilling crew that the drill bit has been worn by the pre-determined amount and requires replacement. The drill stem and bit may then be removed from the hole and while being withdrawn fluid may be circulated through duct 16. However, if it is desired to maintain maximum circulation through the drill stem while it is being withdrawn from the hole, flapper 48 may be removed from its position covering duct 16 so that drilling fluid may flow through this duct as well as through duct 15. The uncovering of duct 16 may be accomplished by shutting off the mud pumps maintaining the drilling fluid in drill stem 13 under pressure, at which time the pressure inside drill stem 13 will be equalized with the pressure surrounding the drill stem. With the equalization of these pressures, spring 32 drives piston 28 upwardly until expanding ring 33 is moved adjacent recess 37, at which time ring 33 will engage in recess 37 and prevent further upward or downward movement of piston 28. With piston 28 in this position, flapper 48 again assumes a position which permits drilling fluid to flow through duct 16.

Instead of employing the means shown in Fig. 1 for sealing portion 26 of duct 23 and for indicating bit wear, the arrangement shown in Figs. 4 and 5 may be employed in which outer end portion 26 of duct 23 is shown as being sealed against the passage of fluid therethrough by means of a tube 50 fluidly connected at its upper end with portion 26 and closed at its lower end 51. The walls of tube 50 are affixed to the walls of portion 26 of duct 23 and tube 50 is affixed to blade 12 by suitable means, as by welding. The lower end 51 of tube 50 extends downwardly along blade 12 to a point at least below the lower edge 49 of body 10. Tube 50 may also be positioned on blade 12 in close proximity to reaming edge 20 thereof, if desired. Tube 50 and the space in duct 23 below piston 28 is filled with a substantially non-compressible fluid which will remain in the liquid state while the device of my invention is in use. A lubricating oil may be suitably used.

When the modification of Fig. 4 is employed, wear of bit blades 11 and 12 during drilling eventually exposes lower end 51 of tube 50 to wear and opens it to the passage of fluid. If tube 50 is positioned in close proximity to the reaming edge 20 of blade 12, tube 50 may be opened to the passage of fluid if the bit blades are worn "out of gauge." When tube 50 is open to the passage of fluid trapped below piston 28, piston 28 moves downwardly and outwardly and flapper 48 closes duct 16 as hereinbefore described indicating to the drilling crew that the drill bit should be replaced.

While the drawing illustrates a drill bit having only one mechanism for closing one water course, it will be understood that the device of my invention may be modified to include a plurality of mechanisms similar to that shown, each mechanism being adapted to close one water course. Ordinarily, however, it will be found satisfactory to provide only one such mechanism as shown.

It is obvious that various changes may be made in the device hereinbefore illustrated and described without departing from the spirit of the invention or the scope of the annexed claims.

What I wish to claim as new and useful and desire to secure by Letters Patent is:

1. A drill bit comprising, in combination, a hollow body releasably connectible with a drill stem to a source of drilling fluid under pressure and provided with cutter blades having a cutting face, the body having at least one first duct for each blade connecting the interior of said body with the exterior of said body above each cutter blade and downwardly directed ahead of the cutting face of said blade, said body having at least one second duct fluidly connecting the interior of said body with the exterior of said body above a cutter blade and to the rear of said blade, a seal closing the outer terminus of said second duct adapted to be removed by cutter blade wear, a piston slidably mounted in said second duct for movement from a rearward position to a forward position, means normally maintaining said piston in its rearward position, and a closure member mounted in the interior of said body and mechanically connected to said piston, said closure member being held in a position leaving said first ducts open and unobstructed when said piston is in its rearward position and being movable to close one of said first ducts upon movement of said piston from its rearward to its forward position upon removal of said seal.

2. A device in accordance with claim 1 in which said seal is a plug arranged in said second duct.

3. A device in accordance with claim 1 in which said seal is a tube with its upper end in fluid communication with the outer terminus of said second duct having a closed lower end disposed in the path of cutter blade wear and sealing said second duct against the passage of fluid therethrough.

4. A drill bit comprising, in combination, a hollow body releasably connectible with a drill stem to a source of drilling fluid under pressure provided with cutter blades on the lower end thereof, each of said blades having a cutting face, the body being supplied with at least one first duct for each blade fluidly connecting the interior of said body with the exterior of said body above said cutter blade and ahead of the cutting face of said blade, said body having at least one second duct fluidly connecting the interior of said body with the exterior of said body above said cutter blades and to the rear of the cutting face of said blades, a seal closing the outer terminus of said second duct adapted to be removed by cutter blade wear, a piston slidably arranged within said second duct, said piston being arranged to assume a first position, a second and a third position, a shear pin normally maintaining said piston in its first position, a spring arranged within said second duct to bias said piston to its third position and a closure plate pivotally mounted in the interior of said body and mechanically connected to said piston, said closure plate being arranged to assume a first position leaving an open flow area to said first ducts when said piston is in its first position and movable to a second position preventing flow through one of said ducts when said piston moves from its first to its second position and movable to a third position leaving a flow area to said first ducts when said piston is in its third position.

5. A device in accordance with claim 4 in which the seal is a plug arranged in said second duct to close the outer terminus thereof.

6. A device in accordance with claim 4 in which said seal is a tube in fluid communication

at its upper end with the outer terminus of said duct, said tube having a closed lower end disposed in the path of cutter blade wear and sealing said second duct against the passage of fluid therethrough.

7. A drill bit comprising, in combination, a hollow body releasably connectible with a drill stem to a source of drilling fluid under pressure provided with cutter blades on the lower end thereof, each of said blades having a cutting face, the body being supplied with at least one first duct for each blade fluidly connecting the interior of said body with the exterior of said body above said cutter blade and ahead of the cutting face of said blade, said body having at least one second duct fluidly connecting the interior of said body with the exterior of said body above said cutter blades and to the rear of the cutting face of said blades, said second duct defining an annular recess adjacent its inner terminus, a seal closing the outer terminus of said second duct adapted to be removed by cutter blade wear, a piston slidably arranged within said second duct, said piston being arranged to assume a first position, a second and a third position, a shear pin 25 normally maintaining said piston in its first position, a spring arranged within said second duct

5 to bias said piston to its third position, an expansible annular ring carried by said piston and adapted to expand into the annular recess defined by said second duct for locking said piston in its third position and a closure plate pivotally mounted in the interior of said body and mechanically connected to said piston, said closure plate being arranged to assume a first position leaving an open flow area to said first ducts when said piston is in its first position and movable to a second position preventing flow through one of said first ducts when said piston moves from its first to its second position and movable to a third position leaving a flow area to said first ducts when said piston is in its third position.
